UNITED STATES PATENT OFFICE.

JAMES H. NORTHROP, OF TUSTIN, CALIFORNIA, ASSIGNOR TO THE DRAPER COMPANY, OF PORTLAND, MAINE, AND HOPEDALE, MASSACHUSETTS.

BACK BOX-PLATE FOR LOOMS.

SPECIFICATION forming part of Letters Patent No. 630,097, dated August 1, 1899.

Application filed March 8, 1899. Serial No. 708,175. (No model.)

To all whom it may concern:

Be it known that I, JAMES H. NORTHROP, of Tustin, county of Orange, State of California, have invented an Improvement in Back Box-Plates for Looms, of which the following description, in connection with the accompanying drawings, is a specification, like letters and figures on the drawings representing like parts.

10 This invention relates to looms for weaving, and has for its particular object the production of a novel back box-plate whereby the cost of production is reduced and the construction simplified.

15 Heretofore the side and cover of the back box-plate have usually been made as a single piece, and the finishing of the front and rear faces of the side and the under face of the cover have been attended by considerable 20 difficulty and expense, owing to the peculiar shape of the casting. In the present invention the side and cover are made separately and thereafter rigidly connected, the separation of the parts enabling the finishing of the 25 faces to be readily and cheaply effected and providing for the ready replacement of either part when necessary.

Figure 1 is a top or plan view of one end of a lay-beam provided with a back box-plate embodying one form of my invention. Fig. 30 2 is a front elevation thereof. Figs. 3 and 4 are perspective views, slightly enlarged, of the box-plate, cover, and side, respectively, and Fig. 5 is a rear side elevation of the box-plate 35 side.

The lay A, longitudinally slotted at a for the picker-stick P, the lay-sword A^X, hand-rail R, and the back binder B, mounted to rock on the vertical pivot-stud b, may be and 40 are of usual or well-known construction.

The back box-plate cover member C is herein shown as a casting of suitable shape, tapering toward its outer end and provided with a socketed eye c for the pivot-stud b, 45 the inner end of the cover being broadened and slightly upturned, as at c', Figs. 1 and 3, the general shape of the cover member being substantially that of the corresponding portion of box-plates now in use. An ear or 50 projection c² projects rearwardly from the plate, provided with a slightly-elongated hole c³ for the reception of the fastening-bolt c^X, Figs. 1 and 2, by which the cover and side of the box-plate are connected.

The separate side member D of the box-plate (shown separately in Figs. 4 and 5) is 55 cast with a plane front face d and a longitudinal ledge or flange d' on its rear face, at its lower edge, said flange at the outer end being extended to form a foot or support d² for 60 the back binder B to move over.

The top of the side member D is curved at its inner end, as at d³, to fit the under side of the cover C at its inner end, and a rearwardly-extended ear d⁴ on the side member extends 65 beneath the ear c² of the cover when the members are assembled, said ear d⁴ having a hole 20 to receive the fastening-bolt c^X. As best shown in Figs. 4 and 5, the top of the ear d⁴ is made slightly higher than the depth of 70 the casting D, adjacent thereto, to bear against the under side of the ear c² on the cover C, so that only the opposed faces of said ears require to be accurately finished.

The side member D is ribbed on the back adjacent the ear d⁴ to present, as herein shown, 75 four bearings d⁵, which abut against the face of the lay-sword, a hole d⁶ in the side member receiving the top bolt d^X, Fig. 2, by which it is secured to the lay-sword.

When finishing the parts, the front face d of the side member D is readily machined to present a true plane and polished surface, and the bearings d⁵ back of the member D can also be as readily finished, and by reason 85 of the fact that the cover member C is a separate piece its under face can also be easily and cheaply finished and polished.

Having fully described my invention, what I claim, and desire to secure by Letters Patent, is—

A back box-plate for looms, comprising 90 separate cover and side members, said cover member having a rearwardly-extended ear, an ear on the back of the side member rising 95 above the upper edge of the latter, to abut against the ear on the cover member, and a connection to engage said ears and rigidly connect said cover and side members.

In testimony whereof I have signed my name to this specification in the presence of two subscribing witnesses.

JAMES H. NORTHROP.
